UNITED STATES PATENT OFFICE.

ALEXANDER KIRKWOOD FINLAY, OF NEW ORLEANS, LOUISIANA.

SYSTEM OF COALING SHIPS AT SEA.

SPECIFICATION forming part of Letters Patent No. 727,774, dated May 12, 1903.

Application filed May 19, 1902. Serial No. 108,093. (No model.)

To all whom it may concern:

Be it known that I, ALEXANDER KIRKWOOD FINLAY, a citizen of the United States, residing at New Orleans, in the parish of Orleans and State of Louisiana, have invented certain new and useful Improvements in Systems of Coalizing Ships at Sea; and I do hereby declare the following to be a full, clear, and exact description of the invention, such as will enable others skilled in the art to which it appertains to make and use the same.

My invention relates to improved means for coalizing ships at sea while under way and where it is impracticable for two vessels to lie alongside of each other during the operation of coalizing.

Various means have been devised by which bags or other like receptacles containing coal are hoisted to a considerable distance above the water and then are allowed to travel along an inclined rope from the collier to the vessel being coalized; but in this case it is necessary to lift the entire weight of the coal to a considerable height and to allow it to travel over a long curved rope or cable.

The above method has been found not wholly satisfactory in practice, and in my invention I purpose to have a loaded boat passing from the collier to the vessel being coalized and coming back empty. The boat may be loaded from the collier either by a coal-chute or in any other convenient way, and when it reaches the vessel being coalized it is hoisted bodily inboard and the coal is dumped out at the desired point. Since the boat will frequently have to go through a heavy sea-way, it is made completely covered over and water-tight.

My invention will be better understood by reference to the accompanying drawings, in which the same parts are indicated by the same letters throughout the several views.

Figure 1 represents a collier preceding a battle-ship and connected to said battle-ship by a tow-line and also by hauling-lines for the boats. Fig. 2 is a diagram in plan of the arrangement shown in Fig. 1. Figs. 3 and 4 are details showing a plan view and vertical longitudinal section of the boat adapted to be used in the herein-described apparatus, and Fig. 5 shows a pneumatic buffer to equalize the strain on the tow-line.

A represents the collier, which should preferably be in advance of the battle-ship or vessel to be coalized and is connected thereto by a tow-line C. To either or both ends of this tow-line a surge-reliever—such, for instance, as a pneumatic buffer D—is connected. The purpose of this is to ease the strain on the tow-line when either vessel pitches in a seaway. By providing suitable buffers it would be possible to make the tow-line comparatively short, and thus shorten the trip of the coal-carrying boats through the water. It will be understood that ordinarily in towing the distance between the vessel towing and the one being towed is considerable, and the tow-line is in the form of a catenary curve, which curve yielding vertically more or less enables either vessel to pitch a reasonable amount without subjecting an excessive or breaking strain on the tow-line; but by employing a pneumatic buffer, as will be hereinafter described, the length of the tow-line may be materially lessened. The preferred form of buffer is shown in Fig. 5, where D' represents a long cylinder, in which is mounted the air-tight piston D², connected to the piston-rod d, which passes through a suitable stuffing-box in the cylinder-head. The eyes d¹, secured to the cylinder D', and d², secured to the piston-rod d, are provided for connecting this buffer to the tow-line and to the vessel, respectively. Air under pressure is supplied through the pipe d⁴ from any suitable source. This would ordinarily be pumped in occasionally when desired. The opposite end of the cylinder in rear of the piston is perforated, as at d⁷, to prevent the accumulation of any compressed air in the rear of the piston, so that the piston and cylinder would normally occupy the position shown in Fig. 5 except when heavy strains are on the tow-line, when the piston would be moved to the right, compressing the air in the closed end of the cylinder D', thus acting as a pneumatic buffer. Since the cylinder would tend to fly forward again when the strain on the tow-line is released, I provide a suitable buffer d³, of rubber or other material, on the piston-rod, which arrests the forward travel of the piston and the cylinder on said rod.

The collier and the vessel to be coalized are

provided with suitable booms or outriggers F and F', between which are hauling-lines, preferably of steel-wire ropes E. The boats H are hauled backward and forward by means 5 of these hauling-lines. They of course have suitable connections inboard; but these are mere mechanical details, which would be obvious to any seafaring man and which would only add to the complexity of the drawings 10 without conveying any additional idea of the system. I prefer to have the collier lead, for the simple reason that it is easier to haul an empty boat ahead than it is to haul a loaded boat ahead. By this arrangement the loaded 15 boat may be eased down to the battle-ship and the empty boat hauled back to the collier. The boats may be loaded on the deck of the collier, then hoisted outboard, eased down to the battle-ship, and hoisted inboard 20 from suitable derricks or davits, (not shown,) or the boats may be coaled from a chute over the side of the collier and then eased down to the battle-ship and hoisted inboard, emptied, and hoisted out of the boat again and sent 25 back to the collier. Davits suitable for this purpose are well known and not being a part of my present invention are not shown herein.

Suitable constructions of boats for the purpose herein described are shown in Figs. 3 30 and 4, in which the boats are provided with a central or coal-carrying compartment H' with end compartments H². These end compartments are made air-tight, like those in a life-boat, and are separated from the compartments H' by means of the bulkheads h². The boat is decked over and is provided with a central water-tight door H³, hinged, as at h³, and provided with suitable fastening devices h⁴, by means of which the said door may be 35 firmly forced down on its seat and may prevent the leaking in of water as the boat is drawn ahead. It will frequently happen that the boat has to dive bodily through the crest of waves, and it is important to make it as 40 absolutely water-tight as practicable. Suitable eyebolts h⁵ are secured to the bow and stern of the boat to connect it to the hauling-line E, and other eyebolts h⁶ are provided for hoisting the boat out of the water. For convenience in dumping the boat it is preferably 45 provided with trunnions H⁴, which project through the stem and stern posts and have their inner ends secured in the sockets h⁷, fast to the partition h². These trunnions lower 50 into the trunnion-seats on the frames K, which may be mounted on the deck at or near the coal-bunker. The boat may be rocked through the desired angle about these trunnions, and the coal may be dumped out, or 55 in case it is necessary to move the boat for a greater or less distance along the deck wheels L and a caster M may be provided, by means of which the boat may be pushed along the deck by hand and the coal dumped out at the 60 desired spot. The boat should preferably be made of pressed steel or wrought-iron, with

stout angle-irons at the joints and so constructed as to stand rough usage.

While I have only shown one boat on each hauling-line E, it is obvious that two or more boats may be placed on each hauling-line, if desired. It will also be obvious that various modifications in the construction of the boat and the pneumatic buffer may be used which could be used without departing from the 75 spirit of my invention.

Having thus described my invention, what I claim, and desire to secure by Letters Patent of the United States, is—

1. In an apparatus for coaling ships at sea, 80 the combination with the collier and the vessel to be coaled, of a tow-line connecting the two, outriggers from the two vessels, one or more hauling-lines connecting said outriggers and one or more boats on each hauling-line 85 adapted to carry coal, substantially as described.

2. In an apparatus for coaling ships at sea, 90 the combination with a collier and a vessel to be coaled, a tow-line connecting the two, outriggers projecting from each vessel, hauling-lines connecting said outriggers, and boats completely housed over and adapted to carry coal, connected to said hauling-lines, substantially as and for the purpose described. 95

3. In an apparatus for coaling ships at sea, 100 the combination with a collier and the vessel to be coaled, of a tow-line connecting the two, a pneumatic buffer at one or both ends of said tow-line, outriggers from the two vessels, 105 a hauling-line connecting said outriggers, and a boat attached to said hauling-line adapted to carry coal, substantially as described.

4. In an apparatus for coaling ships at sea, 110 the combination with the collier and the vessel to be coaled, a tow-line connecting the said vessels, a pneumatic buffer at one or both ends of said tow-line, one or more hauling-lines connecting said vessels, and one or more boats on each hauling-line adapted to carry 115 coal, substantially as described.

5. In an apparatus for coaling ships at sea, 120 the combination with a collier and a vessel to be coaled, a tow-line connecting the two, hauling-lines connecting said vessels and boats 125 completely housed over and adapted to carry coal, connected to said hauling-lines, substantially as and for the purposes described.

6. In an apparatus for coaling ships at sea, 130 the combination with the collier and the vessel to be coaled, of a tow-line connecting the two, a surge-reliever on said tow-line, outriggers from the two vessels, one or more hauling-lines connecting said outriggers and one or more boats on each hauling-line adapted 135 to carry coal, substantially as described.

In testimony whereof I affix my signature in presence of two witnesses.

ALEXANDER KIRKWOOD FINLAY.
